UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

Application filed November 8, 1922. Serial No. 599,621.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

The object of the invention is to provide a friction shock absorbing mechanism especially adapted for railway draft riggings and wherein is obtained high frictional capacity by means of a friction-creating unit so designed as to obtain a compound differential action during compression.

In the drawing forming a part of this specification, Figure 1 is a horizontal longitudinal sectional view of a portion of a railway draft rigging showing my improvements in connection therewith, parts being broken away in order to better accommodate the view on the sheet. Figure 2 is a front end elevation of the shock absorbing mechanism proper. Figure 3 is a vertical transverse sectional view of the shock absorbing mechanism proper corresponding to the line 3—3 of Figure 1. And Figure 4 is a detail perspective of one of the friction elements employed in my mechanism.

In said drawing, 10—10 denote channel draft sills of a car underframe, to the inner faces of which are secured front stop lugs 11 and rear stop lugs 12. A portion of a drawbar is indicated at 13, the same being operatively associated with a hooded cast yoke 14 within which is disposed the shock absorbing mechanism proper and a front follower 15. The yoke and parts therewithin are supported in operative position by a detachable saddle plate 16.

The improved shock absorbing mechanism proper, as shown comprises a combined friction shell and spring cage casting A; a spring resistance B; a plurality of primary wedge-friction elements C—C; a plurality of co-acting wedge-friction-shoes D—D; a plurality of tertiary wedge-friction elements E—E; a plurality of quaternary wedge-friction-shoes F—F; and a retainer bolt G.

The casting A, as shown, is of rectangular cross section, having top and bottom walls 17—17, side walls 18—18, and integral rear vertical wall 19, the latter being laterally extended and suitably reinforced so as to adapt it to cooperate with the rear stop lugs of the draft rigging. The side walls 18, near the outer end of the casting A, have their inner sides converged inwardly of the shell, so as to provide flat shell friction surfaces 20—20. The remainder of the casting A provides a casing or cage for the two-coil spring resistance B.

The primary wedge-friction-shoes C are three in number and vertically spaced, as shown best in Figures 2 and 3. Each of said elements C is of triangular form having a front transversely extending flat face 21, a side flat friction surface 22, and an inclined wedge face 23. The three friction elements C directly receive and transmit the actuating forces from the front follower 15 and all three cooperate with the same friction shell surface 20, viz: the one appearing at the bottom as viewed in Figure 1. Due to the fact that said three elements C are all engaged by the front follower 15, it is evident that they will operate substantially as a single unitary structure, and together constitute what may be considered a pressure-transmitting and receiving wedge-friction-shoe cooperable with one of the surfaces of the friction shell. The secondary wedge-friction elements D are also three in number, the same being vertically separated as best indicated in Figure 3, said elements lying in the same planes as the primary friction elements C. Each of said elements D is of triangular outline, having an outer flat friction surface 24, cooperable with the corresponding adjacent friction surface 20; an inclined wedge face 23, co-acting with the wedge face 23 of the corresponding element C; and an inner transverse edge 25. From an inspection of Figure 1, it will be noted that the outer ends of said elements D are spaced from the front follower 15 and the inner edges 25 are spaced from and out of contact with respect to the spring B.

The tertiary wedge-friction elements E are also three in number and are alternated, vertically, with the secondary wedge-friction elements D, as best shown in Figure 3, said elements E being on the same side of

the axis of the mechanism, as the elements D. Each element E is provided on its outer side with a longitudinally extending friction surface 26, which cooperates with the 5 adjacent friction shell surface 20, the same shell surface as that with which the elements D cooperate. Each element E further is provided with a front transversely extending edge 27 which is in spaced relation 10 with respect to the front follower 15. Along its inner edge, each element E is provided with a wedge face 28, the wedge faces 28 being inclined in the opposite direction to that of the wedge faces 23 and 123. The 15 six elements D and E are provided with vertically aligned openings 29, through which is extended the correspondingly shaped pin 30, from which construction it will be evident that all of said elements D and E will 20 necessarily move and act in unison, both with respect to their inward and outward movements and their movements laterally of the shell, as hereinafter explained. In this 25 connection, it may be observed that the three elements D, due to the pin 30, may be considered as one wedge-friction-shoe and similarly the three elements E may be considered as another wedge-friction-shoe.

The quaternary friction elements F are 30 three in number, the same being alternated with the primary friction elements C and disposed in the same transverse planes as the tertiary friction elements E, as clearly shown in Figure 3. Each of the quaternary 35 friction elements F is provided on its outer side with a longitudinally extending friction surface 31, cooperable with the same shell friction surface 20 as that with which the primary friction elements C cooperate. 40 On its inner side, each element F is provided with a wedge face 128 cooperating with the respective wedge face 28 of an element E. At its inner end, each element F is provided with a transverse face 132, said 45 faces 132 being disposed inwardly of any other parts of the other friction elements C, D and E, so as to insure the forward end of the spring resistance bearing upon said elements F only.

50 The retainer bolt G is anchored at its inner end within a hollow cup-shaped boss 33, formed integrally with the casting A and at its forward end is provided with an eye 34, through which is extended vertically 55 an anchor pin 35, the latter engaging correspondingly sized openings in the primary friction elements C. Where the anchor pin 35 passes through the quaternary friction elements F, the openings in the latter are 60 made larger than the diameter of the pin 35, as indicated at 36 in Figure 1 so that there is thus allowed freedom of movement of the elements F with respect to the pin 35. As will be understood by those skilled 65 in the art, the four central friction ele-

ments C, D, E and F, as best viewed in Figure 3, will be suitably cut away along their adjacent corner edges, as indicated at 70 37, to accommodate the shank of the bolt and the two center friction elements C and E will be suitably recessed as indicated at 38 to freely accommodate the eye of the bolt. With this construction, it is evident that the over-all length of the mechanism can readily be determined by the retainer bolt G, inasmuch as the outward movement of the elements C is limited thereby with 75 respect to the friction shell.

The operation of the mechanism during a compression stroke, assuming a buffing 80 action of the draft rigging, is as follows. As the front follower 15 is moved inwardly, the three friction elements C, constituting what may be termed a primary wedge-friction-shoe, are moved in unison therewith. Said elements C co-acting with the elements D directly, will force the latter inwardly of the shell, and due to the taper of the shell surfaces 20, a differential action will be set up between the primary elements 85 C and the secondary elements D, the latter advancing at a faster rate than the elements C, as will be obvious. Inasmuch as the elements D are so connected to the tertiary elements E by means of the heavy 90 pin 30 that all move in unison, it is evident that the elements E will travel longitudinally and laterally in unison with the elements D. As inward movement of the elements E is thus induced, the quaternary 95 friction elements F will be forced inwardly of the shell. Due to the taper of the shell surfaces, a differential action will be set up between the elements E and F, causing the 100 latter to advance at a faster rate than the elements E. The spring resistance takes place against the elements F and it will be observed that the latter are given a combined acceleration acquired in part from the differential action of the first set of 105 friction elements C and D and in part from the differential action of the second set of 110 friction elements E and F.

From the preceding description, it will be seen that the spring resistance, as ultimately transferred to the primary set of friction elements, is greatly augmented as its effect is transferred first from the quaternary friction elements to the tertiary friction elements, thence from the latter by 115 means of the secondary friction elements, to the primary friction elements. In this manner, I am enabled to obtain very high capacity by the use of a single spring resistance and without the necessity of employing any acute wedging angles. Furthermore, all of the friction elements C, D, E and F, can obviously be manufactured 120 at comparatively small expense and may easily be renewed so that the mechanism 125 130

is not only economical with regard to first cost but also in upkeep.

I have herein shown and described what I now consider the preferred manner of carrying out the invention, but the same is merely illustrative and I contemplate all changes and modifications that come within the scope of the claims appended hereto.

I claim:

10 1. In a friction shock absorbing mechanism, the combination with a friction shell having friction surfaces converged inwardly thereof; of a spring resistance; a set of cooperable wedge-friction-shoes, the shoes 15 co-acting with the friction surfaces of the shell; and a second set of oppositely arranged wedge-friction-shoes also cooperable with the shell.

2. In a friction shock absorbing mechanism, the combination with a friction shell having friction surfaces converged inwardly thereof; of a spring resistance; a set of cooperable wedge-friction-shoes, the shoes co-acting with the friction surfaces of the 25 shell; a second set of oppositely arranged wedge-friction-shoes also cooperable with the shell; and means for communicating the movement of part of the shoes of one set to part of the shoes of the other set.

30 3. In a friction shock absorbing mechanism, the combination with a friction shell having friction surfaces converged inwardly thereof; of a spring resistance; a set of cooperable wedge-friction-shoes, the shoes 35 co-acting with the friction surfaces of the shell; and a second set of oppositely arranged wedge-friction-shoes also cooperable with the shell, some of the shoes of the two sets being rigidly associated and thereby 40 movable in unison.

4. In a friction shock absorbing mechanism, the combination with a friction shell having friction surfaces converged inwardly thereof; of a spring resistance; a set of 45 cooperable wedge-friction-shoes, the shoes co-acting with the friction surfaces of the shell; a second set of oppositely arranged wedge-friction-shoes also cooperable with the shell; and means for limiting the outward movement of one of said sets of friction shoes with respect to the shell.

5. In a friction shock absorbing mechanism, the combination with a friction shell having inwardly converged opposed friction surfaces; of a spring resistance; an outer primary pressure-receiving and transmitting wedge-friction-shoe cooperable with one shell friction surface; a secondary inner co-acting wedge-friction-shoe cooperable 55 with the opposed shell friction surface; a tertiary wedge-friction-shoe cooperable with the same shell friction surface as said secondary friction shoe and movable in unison with the latter; and a quaternary wedge-friction-shoe co-acting with the said ter-

tiary shoe and cooperable with the same shell friction surface as the primary friction shoe.

6. In a friction shock absorbing mechanism, the combination with a friction shell 70 having inwardly converged opposed friction surfaces; of a spring resistance; an outer primary pressure-receiving and transmitting wedge-friction-shoe cooperable with one shell friction surface; a secondary inner co-acting wedge-friction-shoe cooperable with the opposed shell friction surface; a tertiary wedge-friction-shoe cooperable with the same shell friction surface as said secondary friction shoe and movable in unison 75 with the latter; and a quaternary wedge-friction-shoe co-acting with the said tertiary shoe and cooperable with the same shell friction surface as the primary friction shoe, the co-acting wedge faces of said primary and secondary shoes extending in one direction and the co-acting wedge faces of the tertiary and quaternary shoes extending in the opposite direction.

7. In a friction shock absorbing mechanism, the combination with a friction shell having inwardly converged friction surfaces; of a spring resistance; a plurality 90 of primary pressure-receiving and transmitting wedge-friction elements movable in unison; a plurality of secondary wedge-friction elements movable in unison and cooperable with said primary friction elements; a plurality of tertiary wedge-friction elements alternated with said primary 95 and secondary friction elements and movable in unison with the latter; and a plurality of quaternary friction elements co-acting with said tertiary elements and also alternated with said primary and secondary elements.

8. In a friction shock absorbing mechanism, the combination with a friction shell having inwardly converged friction surfaces; of a spring resistance; a plurality 110 of primary pressure-receiving and transmitting wedge-friction elements movable in unison; a plurality of secondary wedge-friction elements movable in unison and cooperable with said primary friction elements; a plurality of tertiary wedge-friction elements alternated with said primary and secondary friction elements 115 and movable in unison with the latter; a plurality of quaternary friction elements co-acting with said tertiary elements and also alternated with said primary and secondary elements; and means limiting the relative separation of said primary friction elements and the shell.

9. In a friction shock absorbing mechanism, the combination with a friction shell having a pair of opposed friction surfaces converged inwardly of the shell; a plurality 130 of primary direct pressure-receiving and

transmitting wedge-friction elements cooperable with one of said shell surfaces; a plurality of secondary wedge-friction elements co-acting with said primary elements and 5 cooperable with the opposed shell surface; a plurality of tertiary wedge-friction elements cooperable with said shell surface with which the secondary elements cooperate; means uniting said secondary and tertiary 10 elements whereby the same move in unison; a plurality of quaternary wedge-friction elements coacting with said tertiary friction elements and cooperable with the same shell friction surface as that with which the primary elements cooperate; a 15 spring resistance interposed between said shell and the inner ends of said quaternary friction elements; and means limiting the outward movement of said primary friction 20 elements with respect to the shell.

10. In a friction shock absorbing mechanism, the combination with a friction shell having a pair of opposed friction surfaces converged inwardly of the shell; a plurality 25 of primary direct pressure-receiving and transmitting wedge-friction elements cooperable with one of said shell surfaces; a plurality of secondary wedge-friction elements co-acting with said primary elements 30 and cooperable with the opposed shell surface; a plurality of tertiary wedge-friction elements cooperable with said shell surface with which the secondary elements cooperate; means uniting said secondary and tertiary 35 elements whereby the same move in unison; a plurality of quaternary wedge-friction elements co-acting with said tertiary friction elements and cooperable with the same shell friction surface as that with which the primary friction 40 elements cooperate; a spring resistance interposed between said shell and the inner ends of said quaternary friction elements; and means limiting the outward movement of said primary friction 45 elements with respect to the shell, the

primary and secondary elements lying in the same planes, the tertiary and quaternary elements lying in the same planes and the primary and secondary elements being alternated with respect to the tertiary and quaternary elements. 50

11. In a friction shock absorbing mechanism, the combination with a friction shell having interior friction surfaces; of a spring resistance; a set of cooperable wedge-friction-shoes, the friction surfaces of the shoes of the set cooperating with opposed friction surfaces of the shell; a second set of oppositely arranged wedge-friction-shoes, the friction surfaces of said shoes also cooperating with opposed friction surfaces of the shell; and means for communicating the movement of part of the shoes of one set to part of the shoes of the other set. 55

12. In a friction shock absorbing mechanism, the combination with a friction shell having interior opposed friction surfaces; of a spring resistance; an outer primary pressure-receiving and transmitting wedge-friction-shoe cooperable with one shell friction surface; a secondary inner wedge-friction-shoe co-acting with the primary friction shoe and cooperable with an opposed shell friction surface; a tertiary wedge-friction-shoe cooperable with the same shell 70 friction surface as said secondary friction shoe and movable in unison with the latter; and a quaternary wedge-friction-shoe co-acting with said tertiary shoe and cooperable with the same shell friction surface as that with which the primary friction shoe cooperates. 75

In witness that I claim the foregoing I have hereunto subscribed my name this 25th day of Sept., 1922.

JOHN F. O'CONNOR.
